US0D1107607S

(12) United States Design Patent (10) Patent No.: US D1,107,607 S
(45) Date of Patent:  Dec. 30, 2025

(54) FOOT FILE

(71) Applicant: Huan Zhang, Jiangsu (CN)

(72) Inventor: Huan Zhang, Jiangsu (CN)

() Term: 15 Years

(21) Appl. No.: 35/522,803

(22) Filed: Sep. 23, 2024

(80) Hague Agreement Data

Int. Filing Date: Sep. 23, 2024

Int. Reg. No.: DM/241309

Int. Reg. Date: Sep. 23, 2024

Int. Reg. Pub. Date: Nov. 1, 2024

(51) LOC (15) Cl. 28-03

(52) U.S. Cl.

USPC D28/59

(58) Field of Classification Search

USPC D28/4, 9, 56, 57, 58, 59, 61, 62, 99
CPC A61Q 3/00; A45D 29/00; A45D 29/18;

A45D 2200/1054; A47K 7/026
